SUPERHEATER

Malcolm Hard, Calumet City, Ill., assignor to The
Superheater Company, New York, N. Y.

Application October 9, 1931. Serial No. 567,853

1 Claim. (Cl. 122—481)

The present invention has to do with boilers generally and more particularly relates to locomotive boilers in which the steam is first superheated by the gas flow from the furnace and subsequently by furnace radiation.

An object of the invention is to protect a radiant superheater subjected to furnace radiation from being burned out particularly during periods of operation when no steam passes through the superheater.

Another object of the invention is to provide a locomotive boiler having a radiant superheater disposed in the furnace of the boiler and supported within close proximity to a water cooled surface comprising a plurality of water circulating tubes in communication with the rear water legs and the space above the crown sheet of the furnace.

Further and other objects of the invention will more fully appear from the following description taken in connection with the accompanying drawings, in which

Fig. 1 is a fragmentary view and partly in section of a locomotive boiler.

Fig. 2 is a fragmentary rear end view of the boiler.

Fig. 3 is a section taken across the line 3—3 of Fig. 1.

Fig. 4 shows a unit of the radiant or secondary superheater.

Fig. 5 is a section taken on the line 5—5 of the inlet portion of the rear header shown in Fig. 2.

Fig. 6 is a section taken on the line 6—6 of the outlet portion of the rear header of Fig. 2.

In accordance with the invention the locomotive boiler includes a furnace 10 in which the radiant superheater, broadly denoted 11, is supported. Mounted at the rear end of the boiler 40 is a header 12 to which leads 13 and 14 of the units of the superheater are appropriately connected. Inlet and outlet portions 15 and 16 are suitably connected to the header, being respectively in communication with chambers 17 and 18 thereof.

Pipes 19 and 20 of a unit are integral with respective leads 13 and 14 and extend longitudinally of the furnace adjacent the crown sheet 21 thereof. These pipes also pass through a thimble or ferrule 22 connected to the spaced walls of the rear water leg 23.

A plurality of spaced water circulating pipes 24 extend longitudinally of the furnace within close proximity and parallel to the radiant superheater pipes 19 and 20.

As illustrated, the water circulating pipes have one end as 25 connected to and in communication with the rear water leg 23 while their other ends 26 are fastened to the crown sheet 21, being in communication with the water and steam space above the crown sheet.

Suitably mounted on the water circulating tubes are the metal spacing members 27. In practice, the tubes are secured to these members in any preferred manner, such as by spot welding. 65 The spacing members also support pipes 19 and 20 of the superheating units and these pipes may also be fastened to the spacing members by spot welding or the like. It is also within the scope of the invention to make the spacing members, 70 if desired, of a suitable refractory heat resisting material.

The water circulating pipes provide a water cooled surface for protecting the pipes of the radiant units and prevent the latter from being 75 burned out especially during periods of operation when no steam passes through the units, as for example when the locomotive engine is at rest.

Associated with the boiler are a plurality of flues 28 for passing the convectional gases from the furnace to the smoke box (not shown), and in these flues the several units of a primary superheater (not shown) are arranged for superheating the steam.

It should be understood that the convectional primary superheater may be omitted and the steam generated be superheated by the radiant superheater alone. Or the radiant superheater 90 may be employed as a primary superheater and the convectional superheater as a secondary, as is well understood.

The superheated steam in the primary superheater is directed into conduit 29 by means well known in the art and is supplied through the inlet portion 15 of the rear header 12 and from the latter is passed through the several superheating units which are subjected to furnace radiation. Subsequently the superheated steam 100 flows through the collecting chamber 18 to the outlet portion 16 of the rear header and is directed into conduit 30 operatively associated with the steam chest of the engine, as is well understood.

Since certain changes may be made in the construction above described and different embodiments of the invention could be made without departing from the scope thereof, it is intended that all matter contained in the above description or shown in the accompanying drawings shall 110

be interpreted as illustrative and not in a limiting sense.

What I claim is:

The combination of a locomotive type boiler having a plate type firebox, a group of water tubes arranged in spaced relation to the sides and crown of said firebox and all connected to receive water from the rear water leg of the boiler and to deliver water, some through the side wall and

some through the crown of the firebox, superheater elements in the space between said water tubes, firebox wall and crown, and inlet and outlet headers for said elements at the rear of the rear face of said boiler, said elements extending through said rear water leg to connect with said headers. 80
